CLAIM

(57) The ornamental design for a bowl of a micro puree machine, as shown and described.

DESCRIPTION

FIG. 1 is a top, front and right side perspective view of the bowl of a micro puree machine of our new design; FIG. 2 is a bottom, rear and left side perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof; and,

FIG. 8 is a bottom plan view thereof.

In the drawings, the broken lines depict portions of the bowl of the micro puree machine and form no part of the claimed design.

1 Claim, 4 Drawing Sheets### Related U.S. Application Data

application No. 17/992,263, filed on Nov. 22, 2022, now Pat. No. 11,759,057, which is a continuation of application No. PCT/CN2022/123016, filed on Sep. 30, 2022.
